(57) **CLAIM**

The ornamental design for a gutter guard as shown and described.

DESCRIPTION

FIG. 1 is a perspective view of a gutter guard showing the claimed design.

FIG. 2 is a second perspective view of the gutter guard.

FIG. 3 is a top view of the gutter guard.

FIG. 4 is a bottom view of the gutter guard.

FIG. 5 is a first side view of the gutter guard.

FIG. 6 is a second side view of the gutter guard. The second side view is opposite that of the first side view.

FIG. 7 is a first end view of the gutter guard; and,

FIG. 8 is a second end view of the gutter guard. The second end view is opposite that of the first end view.

The gutter guard is shown with a symbolic break in its length indicated by the dot-dashed lines. The appearance of any portion of the article between and including the dot-dashed lines forms no part of the claimed design.

The dash-dash broken lines in the figures depict portions of the article that form no part of the claimed design.

1 Claim, 8 Drawing Sheets
